PAGE 2

F1 G = 3

F1 G = 4

FIG. 1 is a perspective view of a game table showing my new design;

FIG. 2 is an end elevational view thereof;

FIG. 3 is a side elevational view thereof with the leg members shown partially in fragment;

FIG. 4 is a top plan view thereof;

FIG. 5 is a perspective view of a second embodiment thereof;

FIG. 6 is an end elevational view thereof;

FIG. 7 is a side elevational view thereof with the leg members shown partially in fragment; and

FIG. 8 is a fragmentary cross sectional view of the side rail and ledge of the table shown in Fig. 1.

I claim:

The ornamental design for a game table, substantially as shown and described.
